INC., OF PROVIDENCE, RHODE ISLAND, A CORPORATION OF RHODE ISLAND.

SAFETY-CATCH.

1,262,777.

Specification of Letters Patent. Patented Apr. 16, 1918.

Application filed February 14, 1916. Serial No. 78,108.

To all whom it may concern:

Be it known that I, CHARLES A. GOOZEY, a citizen of the United States, and resident of the city of Providence, in the county 5 of Providence and State of Rhode Island, have invented certain new and useful Improvements in Safety-Catches, of which the following is a specification.

This invention relates to improvements in 10 safety catches for pins such as those used on breast pins, brooches and other expensive jewelry. The object of this invention is to provide a lock that is strong and very durable and one that will not deteriorate by 15 hard and constant usage. The catch is for the purpose of receiving and securing the pointed end of the pin tongue so as to effectually prevent the same from becoming released or unfastened and so prevent the 20 loss of the article to which it is attached.

A further object of this invention is to provide such a safety catch having a hook and shank portion and a swinging member pivoted in the shank portion and adapted 25 to be moved across to close the mouth of the shank and to provide means for frictionally engaging the swinging member on both sides and releasably retain it either in open or closed position.

With these and other objects in view, the invention consists of certain novel features of construction, as will be more fully described, and particularly pointed out in the appended claim.

In the accompanying drawings:

Figure 1— is a side elevation showing a pin with my improved catch as retaining the pointed end of the pin stem.

Fig. 2— shows the blank from which the 40 hook and its shank are formed as constructed from sheet stock.

Fig. 3— is an enlarged sectional elevation of the hook and shank members.

Fig. 4— is a perspective view of the clos- 45 ing lever removed from the hook member.

Fig. 5— is a sectional side elevation showing the lever mounted in the hook member and moved to closed position.

Fig. 6— is the same as Fig. 4, but with 50 the lever moved to open position.

Fig. 7— is a top view showing the spring fingers as retaining the lever in closed position.

Fig. 8— is the same as Fig. 6, but show-

ing the operating arm as retained in open 55 position by the spring fingers.

Fig. 9— is a near view of the hook member with the lever member removed.

Fig. 10— is a modification showing the pin receiving portion located on the top of 60 the shank instead of on the side thereof.

Referring to the drawings 10 designates the hook which is provided with a shank portion 11, the whole being preferably stamped out of sheet stock originally in the 65 general form illustrated in Fig. 2. From the upper end of this blank the hook portion 10 is formed by being bent over forwardly then the edges 12 of the shank are folded rearwardly providing side walls 13 70 from which extend the yieldable fingers 14, the extremities of which extend inwardly toward each other, which are for the purpose presently described, and the back portion of this shank is provided with an 75 elongated slot 15. An extension portion 16 is provided forming two side wings, which are preferably folded under as illustrated at 17 in Fig. 9 forming a broad base by which the hook may be soldered or otherwise secured to the back of the pin or brooch.

In the lower part of the shank portion and between the side walls 13 is pivoted a lever which is provided with two arms, 85 one arm 20 being arranged to extend through the slot or opening 15 in the shank and is adapted to swing across the mouth of the hook to close the same when desired. This lever is also provided with an operating arm 21 which extends upwardly and rearwardly between the side walls 13 and between the yieldable fingers 14 in such position, that when moved to closed position the extremity of these fingers will 95 reach around and engage the back edge of this operating arm and so releasably hold the lever in closed position, and when the lever is thrown to this open position these fingers will engage the inner edge of the 100 operating arm and so releasably hold the same in open position.

The upper end 23 of this lever is provided with an extension which sets back from the hook so that it may be readily engaged by the operator to swing the lever to the position desired.

By my improved construction I am

enabled to produce a safety catch that works between two opposing resilient walls whereby it is very strong and durable and cannot wear out or get out of order by any amount of usage, this catch being very effective in its operation and one which is also inexpensive to construct.

The modification illustrated in Fig. 10 shows substantially the same mechanism as that above described with the exception that its shank 25 is provided with a U-shaped opening at its upper end instead of a hook portion formed on its side, which opening is adapted to be closed by the finger 27 formed on the lever 26, the same being pivoted at 28 near the bottom of the shank and this lever is releasably held either in open or closed position by the spring fingers 29.

I have shown and described one construction of my safety catch but its details of construction may be altered if desired without departing from the spirit and scope of this invention as it is understood that the terms employed although specific are used in a generic and descriptive sense and not

for the purpose of limitation, the broad idea being that the closing member is designed to operate between the resilient walls which engage the same on both sides so to so yieldingly retain it either in operative or in inoperative position as desired.

I claim:

A safety catch comprising a sheet metal body member having an attaching base and a pin-tongue receiving opening, said body being shaped to provide parallel side walls which are provided with integral resilient extensions having inturned extremities, a lever member having an arm adapted to close said opening, and means for pivotally supporting said lever in a position to swing wholly past said inturned extremities when shifted to either extreme of its movement whereby it is releasably retained in either open or closed position.

In testimony whereof I affix my signature in presence of a witness.

CHARLES A. GOOZEY.

Witness:

A. F. MACREADY.
